UNITED STATES PATENT OFFICE.

JOHN R. DEAN, OF NEW BRITAIN, CONNECTICUT, ASSIGNOR TO INTERNATIONAL SILVER CO., OF MERIDEN, CONNECTICUT, A CORPORATION OF NEW JERSEY.

DESIGN FOR A SPOON, FORK, OR SIMILAR ARTICLE.

41,066.

Specification for Design.

Patented Jan. 3, 1911.

Application filed November 3, 1910. Serial No. 590,557. Term of patent 7 years.

To all whom it may concern:

Be it known that I, JOHN R. DEAN, a citizen of the United States, residing at New Britain, in the county of Hartford and State of Connecticut, have invented a new and original ornamental Design for a Spoon, Fork, or Similar Article; and I do hereby declare the accompanying drawing to be a full, clear, and exact illustration of the same, and which said drawing constitutes part of

this specification and represents a face view of a spoon, fork, or similar article embodying my design.

I claim.

The ornamental design for a spoon, fork or similar article, as shown.

JOHN R. DEAN.
